(57) **CLAIM**

The ornamental design for a light housing as shown and described.

DESCRIPTION

FIG. 1 is a front perspective view of a light housing, showing our new design;

FIG. 2 is a back perspective view thereof;

FIG. 3 is a side plan view thereof;

FIG. 4 is another side plan view thereof;

FIG. 5 is a top plan view thereof;

FIG. 6 is a bottom plan view thereof;

FIG. 7 a front plan view thereof; and,

FIG. 8 is a back plan view thereof.

The features shown in broken lines in the foregoing drawings form no part of the claimed design.
